ORNAMENTAL DOOR

Ronald J. Mathies, Kirkland, Wash., assignor to Simpson
Timber Company, Seattle, Wash.

Filed July 12, 1971, Ser. No. 161,389

Term of patent 14 years

Int. Cl. D25—02

U.S. Cl. D13—1 M

FIG. 1

FIG. 2

FIG. 3

FIG. 1 is a front elevational view of the door embodying my new design, the door having wood insert panels in the top and bottom thereof;

FIG. 2 is a front elevational view of the door embodying my design having glass insert panels in the top thereof and wood insert panels in the bottom thereof;

FIG. 3 is a front elevational view of the door embodying my new design having glass insert panels in the top and bottom thereof.

The rear of the door not shown is the same in appearance as the front as shown in the respective figures.

I claim:

The ornamental design for an ornamental door, as shown and described.
